UNITED STATES PATENT OFFICE.

CHARLES H. REINISCH, OF NEW YORK, N. Y.

MACHINE FOR MAKING AND TWISTING CHAIN-LINKS.

SPECIFICATION forming part of Letters Patent No. 310,317, dated January 6, 1885.

Application filed April 18, 1884. (No model.)

To all whom it may concern:

Be it known that I, CHARLES H. REINISCH, of the city, county, and State of New York, have invented a new and Improved Machine 5 for Cutting, Bending, and Twisting Links for Chains, of which the following is a full, clear, and exact description.

My invention relates to a machine for making quarter chain-links, which machine comprises a revolving mandrel, over which the 10 links are shaped, stationary and movable cutting-edges for cutting the links, and means for grasping and holding, and at the same time twisting, the links.

15 The invention consists of the means for revolving the mandrel intermittently, of the means employed for cutting and grasping the links while the twist is being formed, of the means employed for twisting the links, of the 20 employment of a holding-bar to act in connection with the main cutting-lever, whereby the holding-bar will automatically adjust itself to any irregularity in the rod or wire from which the links are being formed, of the means for 25 operating the main cutting-lever and twister; also, of the general construction, combination, and arrangement of the parts of the machine, all as hereinafter described and claimed.

Reference is to be had to the accompanying 30 drawings, forming part of this specification, in which similar letters of reference indicate corresponding parts in all the figures.

Figure 1 is a plan view of my invention. Fig. 2 is a broken side elevation of the same. 35 Fig. 3 is a sectional plan view, taken on the line $x-x$ of Fig. 2. Fig. 4 is a sectional elevation, taken on the line $y-y$ of Fig. 2. Fig. 5 is a perspective view showing the stationary cutter and guide for the rod or wire from 40 which the links are cut. Fig. 6 is a side elevation of the mandrel removed from the machine. Fig. 7 is a front elevation of the mandrel, showing the rod or wire from which the links are cut wound around it, and held by 45 the clamp-wheel; and Figs. 8 and 9 show, respectively, side and end views of the twister removed from the machine.

A represents the main frame of the machine, constructed of cast-iron, preferably, 50 and with the table A', of such appropriate size

and form as to properly receive and support the operating mechanism.

B is the main shaft, on which are fixed the pinions a a' , and the two pulleys b —one fast and one loose. The pinion a meshes with the 55 large gear-wheel C, which has the large cam c , the short segmental rack d , and outer cam, e , formed upon its inner surface for operating, respectively, the cutting-lever D, the toothed segmental bell-crank E, for turning the twister 60 F, and the lever G, for raising and lowering the twister F, all in the manner and for the purposes hereinafter described. The pinion a' meshes with the intermediate gear, H, and this gear H meshes with the gear-wheel I, 65 placed loosely upon the short heavy shaft I', journaled in the heavy boxes I' I'.

Keyed fast to the shaft I', between the gear-wheel I and the journal-box I', is the disk J. This disk J is provided with the pivoted dog 70 f, which is pressed toward the gear-wheel I at one end by the spring f', for causing the lug f² of the dog to engage with the lug f³, formed upon the gear-wheel I, for locking the wheel I and disk J together.

Upon the journal-box I' is formed or secured 75 the toe g, against which the projection f⁴ of the dog f is adapted to strike at the proper time for disengaging the projection f² of the dog f from the lug f³ on the gear-wheel I, thus 80 permitting the wheel I to make a complete revolution independently of the shaft I' and disk J before locking again with the disk J. In this manner, while the wheel I revolves continuously, an intermittent rotary motion 85 is imparted to the disk J and shaft I', and also to the mandrel K, which is attached to the inner end of the shaft I' by the square shank k of the mandrel entering a corresponding socket made in the shaft, as shown clearly in Fig. 6. 90 The rod or wire L, from which the links are cut, is fed to the stationary guide and cutter M of the machine over the said mandrel K, and the mandrel is made elliptical in form in cross-section, as shown in Fig. 7, for shaping the 95 links. The rod or wire L, as it coils around the mandrel K, is made to conform to the shape of the mandrel by the roller h, under which the wire or rod passes, which roller h is journaled upon the pivoted arm h', which is 100

pressed downward by the strong spring h^2 , the pressure of which may be regulated by the thumb-screw h^3 , as will be clearly understood from Fig. 2.

5 m is the cutting-edge of the stationary guide and cutter M. The guide and cutter M is held in horizontal position and so as to stand at an acute angle with the mandrel K by the keepers M' M', bolted to the top plate, A', of the frame of 10 the machine, and these keepers may be made adjustable for varying the angles of the guide and cutter, and the guide and cutter M is made trough-shaped and diagonal at its cutting end m' , and is so placed in the machine that the 15 diagonal end m' stands partially under the mandrel K, so that the edges m^2 m^2 serve to force the coils of the wire or rod L off from the mandrel K, and also to properly spread the coils so that the knife i, secured to the short 20 arm d' of the cutting-lever D, may enter between the coils, so as to act against the cutting-edge m for cutting the links N one by one from the wire or rod L, as will be understood from Figs. 3 and 5. The cutting-lever 25 D is pivoted upon the stud j, and its main long arm d^2 is adapted to be forced outward, causing the knife i to approach the cutting-edge m by the above-mentioned cam e, formed upon the large gear-wheel C, and is adapted 30 to be drawn inward by the spring O, which acts through the transversely-arranged bar P, to be hereinafter described. After each link 35 N is cut from the rod or wire L by the outward movement of the long arm d^2 of the cutting-lever D, the ends of the link are grasped between the end n of the swinging holding-bar Q, and the face of the knife i, which will hold the link firmly in vertical position, as shown in Fig. 2, until the twister F descends upon 40 the folded end of the link, and is turned by means described below, for giving a one-quarter twist or turn to the link. After the twist has been formed in the link, the machine being in continuous operation, the cam e on 45 large wheel C will have passed the end of the long arm d^2 of the cutting-lever D, leaving it free to the action of the spring O, which will act to draw the transverse bar P, the end n of the holding-bar Q, together with the arm d' of 50 the cutting-lever D, from the position shown in Fig. 3 to that shown in Fig. 1, which movement will release the link N and permit it to drop down through the machine completed—that is, formed and twisted. The holding-bar 55 Q is divided at its rear end to form the arms k k , and is placed upon the hub l, which fits loosely in a socket made in the top plate, A', so as to be adapted to turn therein, and the hub l is transversely screw-tapped to receive 60 the screw-bolt l'. The point end of this bolt l' is reduced in size, and the reduced portion is passed through the lug l'', formed upon the under side of the bar Q, and riveted, as shown in dotted lines in Figs. 1 and 3 and in full lines in Fig. 2, so that by turning the screw-bolt l' to the right or left, the bar Q will be forced 65 forward or backward, being guided in its move-

ment by the arms k k , which pass either side of the hub l. When the proper longitudinal adjustment of the bar Q is obtained by turning-screw l', the bar Q will be made fast to the stud l by turning down the nut l', placed upon the upper reduced and screw-threaded portion l' of the hub l, which will lock the bar Q and the hub l securely together. The 75 holding-bar Q is yoked to the cutting-lever D by the above-mentioned transversely-arranged plate P, which is connected with the holding-bar Q by the stud o, formed upon the bar P entering a hole, o', made in the holding-bar Q, and bar Q is yoked with the cutting-lever D by the flange p and screw p' passed through the flange p, so that its inner end rests against the outer edge of the cutting-lever D, as clearly shown in the drawings. The opposite end of 80 the bar P is formed with the hook p'' for connection with the spring O, the office of which spring, as above described, is to return the bar P, and with it the holding-bar Q and cutting-lever D, to their original position after 85 the cam e passes the end of the cutting-lever D. The end n of the holding-bar Q is made slightly diagonal, and this bar being connected to the cutting-lever D by bar P, it follows that when the lever D is forced outward by 90 the cam e the front end, n , of the bar Q will be drawn forward (the bar turning the hub l) to stand in front of and parallel with the knife i of the cutting-bar D. By adjusting the screw l' the space between the end n of bar Q and 95 the knife i may be increased or diminished as required, according to the size of the rod or wire L from which the links are to be cut, and, owing to the direct longitudinal movement of the bar Q, caused by turning the screw 100 l', the proper parallelism between the end n and the knife i will always be maintained at the time of cutting the link. The end n of the bar Q being held in front of the knife i at the time of cutting the link, the instant the 105 link is cut off from the coil by the knife i acting against the cutting-edge m of the stationary guide and cutting-bar M, the link will be firmly grasped between the end n and the knife i and held as in a vise until the operation of 110 twisting the link (yet to be particularly described) is performed, the holding of the parts in this grasping position being effected by the concentric surface c' of the cam e. By the outward movement of the cutting-lever D, effected by the abrupt edge c'' of the cam e, the outer edge of the lever D becomes an inclined 115 horizontal plane, along which the point end of the regulating-screw p' slides until it finds its own seat, which will be at the point where the link N becomes firmly held, be it large or small in diameter, so that the gripping devices for the links in this manner become automatically adjustable to any irregularity in the thickness of the wire or rod L. The twister 120 F is made square with the claw q at its lower end for receiving the link, and it is formed with the flange q' at its upper end for resting upon the fingers r r of the lever G, as shown 125

clearly in Figs. 1 and 2. The square portion of the twister is placed loosely in a square passage made through the collar R held loosely in the ring S, formed at the outer end of the 5 overhanging bracket T, which holds the said collar R and twister F above the stationary cutting-edge *m*. The collar R is formed or provided with the flange *s* to prevent it from dropping through the ring S, and also with the 10 arm U, which is connected by the connecting-rod or pitman V to the segmental bell-crank E, above mentioned, which crank is pivoted upon the stud *t*, so that the teeth *e* thereof will be engaged by the rack *d*, formed upon the 15 large wheel C for causing the bell-crank lever E to turn the collar R and twister F at the proper time to twist the link N. The movement of the segmental bell-crank E will be against the tension of the spring W, which 20 will act to return the bell-crank E, collar R, and twister F to their normal positions after the rack *d* passes the segmental teeth *e'* of the bell-crank E, as will be understood from Figs. 1 and 2. The lever G is fulcrumed upon the 25 same stud *t* that the bell-crank E is pivoted upon, and the end *e*² of the lever is adapted to be depressed by the above-mentioned cam *e* formed at the edge of the wheel C for raising and lowering at the proper time the twister 30 F, so that the claw *q* thereof will engage with the folded end of the link N immediately after it is cut off from the rod or wire L, and while the link is held by the knife *i* and holding-bar Q, and while the twister is being turned 35 for forming the twist or turn in the link.

The operation of the machine is as follows: Power being applied to the fast driving-pulley *b* to cause the main shaft B to be slowly revolved in the direction of arrow No. 1, the 40 pinion *a'*, meshing into the intermediate gear, H, and this gear, with gear-wheel I, will cause the latter to revolve in the same direction with the shaft B, while the pinion *a*, meshing directly with large gear-wheel C, will cause this 45 gear to revolve in the opposite direction—in the direction of arrow No. 2—and this gear C is of such size relative to the size of the gear-wheels H I *a'* that it makes but one revolution while the gear-wheel I makes two complete 50 revolutions. The rod or wire L to be made into links is first given a few turns on a hand-machine and is then slipped over the mandrel K under the pressure-roller *h*, which is brought down firmly upon the first coil of the rod or 55 wire by turning down the thumb-screw *h*³. The slow motion given to the loose cog-wheel I will bring the lug *f*³ thereof in contact with the projection *f*² of the dog *f*, which will cause the disk J and mandrel K to perform one revolution, winding one link upon the mandrel 60 and one link off into the guide M between the cutters. The dog *f*, by the action of the toe *g* upon projection *f*⁴, then releases the lug *f*², thus permitting the loose cog-wheel I to make 65 another revolution while the disk J and mandrel K remain at rest. The instant the lug *f*³ passes the dog *f* the abrupt surface *e*² of the

large cam *e*, formed upon the large gear-wheel C, will force outward the main arm *d*² of the cutting-lever D, causing the knife *i* to approach and pass the stationary cutting-edge *m*, causing the link wound off from the wire or rod L to be cut off. With the outward movement of the main arm *d*² of the cutting-lever D the holding-bar Q will be brought forward by the transversely-arranged bar P, so that as the knife *i* passes the stationary cutting edge *m* the link N will be grasped and firmly held between the knife *i* and the end *n* of the holding-bar Q. At this time the concentric surface *e'* of the cam *e* will have reached the arm *d*² of the cutting-lever D, so that while this concentric surface *e'* of the cam *e* is passing the lever D the knife *i* and bar Q will remain at rest, holding the link. At the time 85 the link is cut, or a little before, the cam *e* on wheel C will depress the end *e*² of the lever G, which will elevate the opposite end of the said lever and cause it to raise the twister F in the collar R and to hold the twister above 90 the link, and during the interval of rest of the bars D and Q and knife *i* while they hold the link the cam *e* will pass the end *e*² of the lever G, which will permit the twister F to drop down in the collar R, so that the claw *q* of the 95 twister will rest upon and engage with the folded end of the link, as shown clearly in Fig. 2. While the twister remains in this position, engaging the link, the rack *d*, formed upon the large wheel C, will come in contact with 100 the teeth *e'* of the bell-crank E, causing the bell-crank, acting through the connecting-rod V, lever U, and collar R, to give the twister F a one-quarter turn, which will put the required twist in the link. This 105 being accomplished, the cam-face *e'* will have passed the main arm *d*² of the cutting-lever D, whereupon the spring O will bring the lever D, plate P, and holding-plate Q, back to the original positions, the finished link falling of 110 its own weight into a box placed beneath the machine, and the instant the cam *e* passes the arm *d*² of the lever D the rack *d* will release the bell-crank lever E, whereupon the spring W will act to return the bell-crank, collar R, and 115 twister F to their original position, ready to repeat the operation. There will be several 120 mandrels K, of different sizes, with each machine, and the mandrels will be interchangeable with each other, so that links of various sizes may be made upon the same machine. The end of the main arm *d*² of the lever D is supported upon the bridge or arm A², forming a part of the main frame A, which arm guides the cutting-lever in its movement and 125 takes the down-thrust of the cam *e*, and the end of this arm *d*² is provided with the roller *d*³ to take the friction of the cam *e*. The stationary cutter and guide M is tempered its 130 whole length, and is so held in the machine that it may be readily taken out and ground and properly adjusted back in the machine, so that a perfectly square and smooth cut of the links may always be effected, insuring a per-

fect joint when the links are put together to form the chain.

Having thus described my invention, what I claim as new, and desire to secure by Letters Patent, is—

1. The mandrel K, held in a shaft, I', in combination with the disk J, made fast to the shaft, and the gear-wheel I, placed loosely upon the shaft, the disk and gear-wheel being provided with clutching and releasing mechanism, whereby continuous rotary motion of the gear-wheel I will impart an intermittent rotary motion to the disk, shaft, and mandrel, substantially as and for the purposes set forth.
2. The combination, with the mandrel K, over which the rod or wire to be made into links is coiled, of the stationary cutter-edge m, and a reciprocating cutting-lever arranged to cut the coils one by one as they are wound off from the mandrel by its intermittent revolution, substantially as and for the purposes set forth.
3. The stationary cutter M, made trough-shaped, and formed with the cutting-edge m, substantially as and for the purposes set forth.
4. The holding-bar Q, yoked to the cutting-lever D, so as to be brought forward by the outward movement of the main arm of the cutting-lever, to act in connection with the knife of the cutting-lever for grasping and holding the links, substantially as and for the purposes set forth.
5. The holding-bar Q, yoked to the cutting-lever D by the plate P, pivoted to the bar Q, and made adjustable by the screw p', whereby the holding-edges for the links will automatically adjust themselves to irregularities in the links, substantially as described.
6. The holding-bar Q, made longitudinally adjustable, in combination with the reciprocating cutting-lever D and yoke-plate P, arranged to operate substantially as and for the purposes set forth.
7. The combination, with the device for cutting and grasping the link, of the twister F, and the means, substantially as described, for raising and lowering and turning the twister, as and for the purposes set forth.
8. The wheel C, provided with the cam c, having the abrupt surface c² and concentric surface c', in combination with the cutting-lever D and the reciprocating holding-bar Q, arranged to be brought forward by the out-

ward movement of the main arm d² of the cutting-lever, substantially as and for the purposes set forth.

9. The combination, with the supporting frame and the mandrel K, of the arm h', pivoted to the frame above the mandrel, the presser-roller journaled on the end of the said arm, the spring h², having its free end resting on the outer end of the said arm, and the thumb-screw h³, engaging the spring, substantially as herein shown and described.

10. The wheel C, provided with the cam c, in combination with the lever G and twister F, held in the sleeve R, arranged above the cutting-edge m, substantially as and for the purposes set forth.

11. The wheel C, having rack d, and the bell-crank lever E, arranged to be turned by the rack, in combination with the collar R, twister F, and connecting-rod V, all arranged to operate substantially as and for the purposes set forth.

12. The main cutting-bar D, arranged to be reciprocated by the cam c, in combination with the holding-bar Q, yoke-plate P, and spring O, arranged to operate substantially as and for the purposes set forth.

13. The bell-crank E, connected to the collar R, held in the bracket T, in combination with the rack d and spring W for reciprocating the collar and lever, substantially as and for the purposes set forth.

14. The holding-bar Q, placed upon the hub l, combined with the screw l', arranged for adjusting the bar Q longitudinally, substantially as and for the purposes set forth.

15. The combination, with the intermittently-rotating mandrel K, stationary guide and cutting-bar M, and reciprocating cutting-lever D, of the longitudinally-adjustable holding-bar Q and adjustable yoke-bar P, arranged to operate substantially as described.

16. The combination, with the intermittently-rotating mandrel K, stationary cutter M, and reciprocating cutting-lever D, of the swing holding-bar P and reciprocating and rotating twister F, arranged to operate substantially as described.
